(57) **CLAIM**

The ornamental design for a control cord safety connector, as shown and described.

DESCRIPTION

FIG. 1 is a perspective view of the control cord safety connector and which illustrates window covering cords in broken line as a part of the environment and forming no part of the invention;

FIG. 2 is a front view identical to a right, left and rear view;

FIG. 3 is a top view; and,

FIG. 4 is a bottom view.
